UNITED STATES PATENT OFFICE

2,143,313

NOISE ELIMINATOR

Homer M. Grotz, Brentwood, N. Y.

Application October 7, 1937, Serial No. 167,824

1 Claim. (Cl. 16—86)

This invention appertains to new and useful improvements in means for eliminating noise in doors and various other closures.

An important object of the invention is to provide means for attachment to a door, door jamb or door stop whereby the shock of slamming a door will be absorbed, and moreover loose doors will be prevented from vibrating due to air currents and the like, thus entirely eliminating noise.

Other important objects and advantages of the invention will become apparent to the reader of the following specification.

In the drawings:—

15 Figure 1 represents a fragmentary edge elevational view of a door, door jamb or door stop equipped with the absorber.

Figure 2 is a fragmentary side elevational view of the door, door jamb or door stop.

20 Figure 3 is a sectional view taken substantially on line 3—3 of Figure 1.

Figure 4 is a perspective view of the spring employed in the form shown in Figures 1, 2 and 3.

25 Figure 5 is an inside elevational view of the device.

Figure 6 is a sectional view showing a modified form of structure.

Figure 7 is an inside elevational view of the modified form of invention.

30 Figure 8 is a perspective view of the inner plate of the form of the invention shown in Figure 3.

Referring to the drawings, wherein like numerals designate like parts, it can be seen that 35 numeral 5 denotes the jamb edge of a door, door jamb or door stop which has a portion rabbeted to accommodate a noise eliminating device, generally referred to by numeral 6. This device consists of the plate 7 having the wall 8 along one longitudinal edge portion, the two end walls 9—9 40 and the face flange 10 which extends the entire length of the plate 7. This plate 7 is provided with openings 11 therein, through which securing elements may be disposed for securing the device in place.

45 The flange 10 is provided with a slot 12 therein through which one longitudinal edge portion of the resilient snubber 13 can project. This snubber 13 is provided with the grooveway 14 therein which receives the beveled rib 15 which projects from the back plate 16. This back plate 16 at one edge, abuts the flange 10 and at its opposite end

is secured by machine screw 17 to the boss formation 18 on the wall 8. A strip spring 19 has its intermediate portion resting against the boss 18 and the end portion of this spring 19 engages against the inner edge portion of the snubber 13. The intermediate portion of the snubber 13 at its inner edge is cut away as at 20.

Thus it can be seen that when the snubber 13 mounted on the door strikes the door jamb or when the door strikes the snubber 13 mounted on the door jamb or stop it will yield inwardly, hard shocks taken up by the steel spring 19.

A modified form of the invention is shown in Figures 6 and 7. This form of the invention discloses the door 5' rabbeted along one edge portion to receive the unit generally referred to by 6'. The unit 6' includes the plate 7' having a longitudinally extended flange 10' inlaid in one side of the door 5'. The flange 10' is provided with a slot 12' through which one edge portion of the snubber 13' projects. The snubber 13' at its mid-point is provided with a longitudinally extending grooveway 14' for receiving the beveled rib 15' projecting inwardly from the plate 7'. In this construction the inner plate 16 is eliminated, the beveled rib being placed directly on the outer plate 7'. A flange 8' extends inwardly from the plate 7' and backs the snubber 13'.

While the foregoing specification sets forth the 30 invention in specific terms, it is to be understood that numerous changes in the shape, size and materials may be resorted to without departure from the spirit and scope of the invention as claimed hereinafter.

35 Having described the invention, what is claimed as new is:—

A snubber of the character described comprising a case having an opening therein, a resilient block slidably disposed in the case and having 40 a portion protruding through the opening, the inner edge portion of the block being provided with an intermediate cut-away portion defining a pocket, an elongated strip spring disposed against the inner edge of the block and bridging 45 the said pocket, the inner most wall of the case being provided with a boss for engaging the intermediate portion of the strip spring at a point opposed to the pocket of the block, and means for limiting the extent of movement outwardly of the said block.

HOMER M. GROTH.
